UNITED STATES PATENT OFFICE.

HENRY W. DIECK, OF BROOKLYN, NEW YORK, ASSIGNOR TO THE STANDARD TEXTILE PRODUCTS COMPANY, OF NEW YORK, N. Y., A CORPORATION OF OHIO.

DESIGN FOR A TABLE COVER OR SIMILAR ARTICLE.

Application filed November 16, 1928. Serial No. 28,912. Term of patent $3\frac{1}{2}$ years.

To all whom it may concern:

Be it known that I, HENRY W. DIECK, a citizen of the United States, residing in the borough of Brooklyn, county of Kings, and State of New York, have invented a new, original, and ornamental Design for Table Covers or Similar Articles, of which the following is a specification, reference being had to the accompanying drawing, forming part thereof.

The figure of drawing is a view in top plan of a table cover or similar article embodying my new and ornamental design, repetition thereof throughout the corresponding portions presented in outline being understood.

The color scheme of my design includes the natural colors of the leaves, roses and other flowers, while the ribbon, loops and corner stems may be any suitable contrasting color.

I claim:

The ornamental design for a table cover or similar article as shown and described.

HENRY W. DIECK.
